UNITED STATES PATENT OFFICE.

HATTIE M. NORMAN, OF SANDUSKY, OHIO; MARY N. EVANS ADMINISTRATRIX OF SAID HATTIE M. NORMAN, DECEASED.

BICYCLE-SADDLE.

SPECIFICATION forming part of Letters Patent No. 653,588, dated July 10, 1900.

Application filed October 14, 1899. Serial No. 733,576. (No model.)

To all whom it may concern:

Be it known that I, HATTIE M. NORMAN, a citizen of the United States, residing at Sandusky, in the county of Erie and State of Ohio, 5 have invented certain new and useful Improvements in Bicycle-Saddles; and I do declare the following to be a full, clear, and exact description of the invention, such as will enable others skilled in the art to which it 10 appertains to make and use the same, reference being had to the accompanying drawings, and to the letters of reference marked thereon, which form a part of this specification.

15 This invention relates to improvements in bicycle-saddles, and has reference to that class of saddles known as "two-pad" or "health" saddles.

The invention consists, essentially, of a pair 20 of air-cushions and suitable plates and containing mechanism for holding them in position between the base-plate of the saddle and the topping or seat leather.

The invention further consists in the novel 25 construction and arrangement of the several parts of the device hereinafter described, illustrated in the drawings, and more particularly pointed out in the claim hereunto appended.

30 In the drawings, Figure 1 is a top view of my saddle, having a portion of one of the pads broken away to show the construction. Fig. 2 is a perspective of one of the pads. Fig. 3 is a cross-section of the saddle, taken 35 through both pads and showing a leather washer between the base and the spring. Fig. 4 is a perspective view of the brace C, and Fig. 5 is a detail showing the washer located between the base-plate and the spring.

40 Referring to the drawings by letters, A represents a saddle-plate, and A' a depression or seat therein of any desired formation and is provided with a suitable opening A² in the bottom thereof.

45 B is a plate or holder of shape to correspond to the shape of the seat in base-plate and is provided with a downwardly-projecting flange B' around its outer edge, in which are formed at desirable intervals holes or 50 openings b for a purpose hereinafter stated. This plate or holder B is also provided with

a suitable circular opening B², adapted to register with the opening A² in the seat in the base-plate.

C is an auxiliary plate adapted to reinforce 55 or strengthen the plate or holder B, and extends across the said holder to the rear of the openings B² and is interposed between said holder and the air-cushion D. The plate C is also provided with flanges having open- 60 ings therein that register with the openings b in the flanges B' of the holder B.

D is a suitable air bag or cushion of the same shape as the holder B and the seat in the base-plate. This cushion rests on the 65 holder B and within the topping or covering of canvas and leather E and F and is of such size as to permit the holder and topping (which constitute a pad of the saddle) to fit snugly in the seat in the base-plate. The 70 cushion D is provided with a valve of the ordinary construction, which when the cushion is in the pad and in position in the seat extends down through the openings B² and A² and projects beneath the saddle-plate. 75

E is a tough piece of canvas or other suitable material used as a protection against the action of the leather (which tends to burn, rot, and destroy the rubber air bag or cushion) upon the cushion D. 80

F is a piece of suitable leather, such as is usually used for saddle pad-covers.

My improved saddle is constructed as follows: The plate or holder B and the openings therein are stamped from a suitable piece of 85 sheet metal and the flanges B' suitably perforated and turned up. The auxiliary plate is then struck off in the same manner and the leather and canvas cut to a desired shape. The plates B and C are then placed together, 90 so that the flanges and openings therein will register. The canvas and leather are then fitted over said plates and permanently or rigidly secured thereto along one side thereof by suitable rivet-eyelets g g. The topping is then 95 turned back and the air bag or cushion placed beneath upon the plates or holder B, with the valve-stem projecting down through the opening B². The topping is then drawn over said bag or cushion and laced to the plate through 100 the holes or openings b in the flanges B'. This pad is then secured removably by suit-

able wires or catches *h h* in the seat A' of the plate A.

To the under side of the saddle between the spring and the base-plate I place a leather cushion or buffer *a* or any other suitable material for the purpose of preventing the grinding of the spring against the base-plate and preventing the consequent disagreeable grinding and creaking noise.

10 Having thus fully described my invention, what I claim is—

In a bicycle-saddle of the character described, the combination of a base-plate provided with a depressed seat having a small opening therein, with a pad consisting of a plate or holder of the shape of the seat or depression and provided with an opening adapted to register with the opening in the

plate, and having its edges turned to form downwardly-projecting flanges, said flanges being provided with suitable holes or openings, a leather topping lined with canvas and rigidly secured to said plate or holder on one side thereof and adapted to be laced to the other edge with suitable lacing, and an air-bag inclosed between the topping and the plate, and means substantially as described for removably holding said pad in position in the seat of the base-plate, as set forth.

20 In testimony whereof I affix my signature 25 in presence of two witnesses.

HATTIE M. NORMAN.
